SASH SUPPORT FOR SASH BALANCE UNIT
 Thomas P. Koebel, Homewood, Ill., assignor to
 Zegers, Inc., a corporation of Illinois
 Filed Sept. 11, 1959, Ser. No. 839,355
 7 Claims. (Cl. 16—197)

My invention relates to a sash balance unit, and more particularly, to a sash support or platform therefor which is particularly adapted to facilitate the application of such supports or platforms to sash balance units.

Many forms of modern window units of the vertically movable sash type include the well-known spring sash balance unit that is composed of a conventional coiled tension spring that is disposed within a groove formed in the side rail of the sash and has one of its ends secured to the window frame jamb to suspend the spring from the building framing structure. The sash is attached to the lower end of the spring by what is known in the art as a sash support or platform.

Sash supports or platforms of the type referred to are conventionally secured to the lower ends of such spring balances by engagement with the lowermost end of the spring wire member that forms the balance. This lowermost end is customarily formed into an open loop that projects axially of the spring and the end of the wire forming the loop is passed through an appropriate eye or other attachment structure defined by the support or platform so that the support or platform hangs or depends from the spring. The spring loop is then closed with pliers or a press to prevent the platform from falling off during subsequent handling.

This manner of attaching the sash support or platform to the balance spring requires a special forming action on the lower end of the spring to define the looped end to which the platform or support is attached. Furthermore, the step of actually applying the platform to the spring looped end is essentially a hand operation because the manipulation of the parts required precludes ready mechanization.

A principal object of my invention is to provide a simplified sash support or platform of the type described above which is adapted to be applied directly and automatically between the convolutions of the spring balance, thus eliminating the need for the additional forming action now required at the lower end of the balance spring.

Still a further principal object of the invention is to provide a simplified sash support or platform which lends itself to mass production purposes.

Another object of the invention is to provide a simplified sash balance structure which is economical of manufacture, convenient to assemble, and readily adapted for use in existing window assemblies without any modification thereof.

Other objects, uses and advantages will be obvious or become apparent from a consideration of the following detailed description and the appended claims.

In the drawings:

FIGURE 1 is a fragmental perspective view of a typical double hung window structure to which a preferred embodiment of my invention has been applied;

FIGURE 2 is an enlarged fragmental perspective view showing a preferred form of my improved sash support or platform applied to a spring balance member, the adjoining portion of the sash being shown in outline;

FIGURE 2a is a fragmental plan view of a lower end of a conventional spring balance member illustrating the open loop that is eliminated by my invention;

FIGURE 3 is a perspective view of the sash support or platform shown in FIGURES 1 and 2, looking at the top portion thereof from the front or outer side thereof;

FIGURE 4 is a perspective view of the support or plat-

2

form shown in FIGURE 3, but looking at the bottom portion thereof from the rear or inner side thereof; and

FIGURES 5 and 6 are elevational views, partially in section, illustrating the manner of assembling my improved sash support or platform to the spring member of the sash balance.

Reference numeral 10 generally indicates a preferred form of my sash support or platform, which, in FIGURE 1, is shown applied to a conventional double hung window structure 12 of a well-known modern style. The window structure 12 includes upper and lower sash, the inner sash being indicated at 14, which ride on tracks 18 that are carried by combination weatherstrip and sash guide members 20. As is well-known in the art, the sash side rails are conventionally formed with grooves 16 that are complementary in shape to the shape of tracks 18. Springs 22, secured between the tops of the members 20 and the bottom rails 23 of the sash, bias the sash upwardly of the window structure.

20 The sash platforms or supports 10 are employed to secure the sash to the lower ends of the respective balance springs 22 so that the bias of the springs 22 is applied to the sash in the manner desired.

Sash balance springs 22 are preferably of the closed convolution type and conventionally are attached, as shown in the arrangement illustrated in FIGURE 1, to the upper ends of weatherstrip members 20 by bending the top two convolutions 25 of the spring into parallelism with the axis of the spring and then slipping the respective webs 24 of the members 20 between the upturned spring convolutions, as generally indicated in FIGURE 1. The upper ends of springs 22 may also be attached to the jamb by a nail or the like extending through loop 27 that is defined by said bent convolutions 25, as is well-known in the art.

30 In accordance with my invention, the usual looped end 26 indicated in the conventional spring 22a shown in FIGURE 2a is omitted and the lower spring end 28 of spring 22 at its terminus 30 (see FIGURE 2) remains part of the convolutions defining spring 22. Platform or support 10 is applied to spring end 28 by being slipped between two adjacent spring convolutions in the manner suggested by FIGURES 5 and 6.

Referring now more particularly to FIGURES 3 and 4, the support or platform 10 comprises a body 32 formed with a relatively flat central web portion 34 and a pair of coplanar oppositely projecting flanges 36 that, in the form shown, are integrally united with the web portion 34. Rising from the upper surface 38 of the web portion is a rounded or arcuate wall 40 which terminates at ends 42 disposed at either end of a thin or tapered edge 44 of the web portion 34.

As seen in FIGURE 4, the lower surface 46 of the web portion is displaced above the lower surfaces 48 of the oppositely extending flanges or wings 36 to define a slot-like seat or pocket 50 that is sufficiently deep to accommodate two, or preferably three, convolutions 72 of spring 22. Projecting downwardly from the lower surface 46 of the web portion 34 is a wedge-shaped lug or protuberance 52 defined by side and end surfaces 54 and 56 and inclined surface 58, which commences diverging from the lower surface 46 of the web portion starting from a point 60 adjacent edge 44 to point 62 in the plane of end surface 56.

60 The circular or arcuate wall 40 is formed with right angle locating corners 64 that are proportioned to engage the opposed sides 65 (see FIGURE 2) within the sash groove 16 to hold the platform in proper alignment with respect to the sash. Corners 64 respectively merge with the forward ends of arcuate wall 40 to define locating planar surfaces 67 at the bases of flanges 36 that extend the width of the platform.

The arcuate wall 40 together with the upper surface 38 of web portion 34 also defines a pocket 66 for receiving adjacent convolutions of the spring 22.

The manner of applying platform or support 10 to the spring 22 to assemble the parts as shown in FIGURE 2, is indicated in FIGURES 5 and 6. It is only necessary to place the thin edge 44 of web portion 34 in contact with a recess 70 defined by an adjacent pair of convolutions 72 and then press the web portion into the center of the spring sufficiently so that the end wall 56 of the wedge-shaped lug 52 is lodged within the center of the spring. The adjacent lower convolutions 72 will be received in pocket 50 while the upper adjacent spring convolutions 72 will be received in the pocket 66.

After the platform or support 10 is applied to the spring 22, the spring 22 may be secured to the window jamb in the manner indicated in FIGURE 2, or in any other suitable manner, after which the spring 22 is tensioned or pulled downwardly of its track 18 to apply the sash to the track 18 of the combination weatherstrip and sash balance unit. As indicated in FIGURE 2, the lower end of the sash rests on the flanges 36, which engage the undersurface of the sash on either side of the sash groove 16.

As already mentioned, shoulders 64 engage within the sash groove 16 so that surfaces 67 will hold the sash platform or support 10 in proper alignment with the sash, and accordingly, the shoulders or corners 64 should be proportioned for proper engagement with the sash rail structure.

The wedge-shaped lug 52 insures that the platform will not be withdrawn from the spring without threading (or rotating) it downwardly past termination 30 thereof.

It should now be apparent that my improved sash platform or support materially simplifies the manufacture and assembly of sash balance units of the type to which the invention relates. Thus, spring 22 may take the form of a simple closed convolution spring which only need be further processed to form the upstanding upper end shown in FIGURE 1. The sash platform or support is readily applied to the lower end of the spring merely by slipping it between two adjacent convolutions. This arrangement adapts the spring balance unit illustrated for assembly by mass production methods in which the supports 10 are automatically inserted or applied to individual springs by machines or appropriate mechanisms employing the steps shown in FIGURES 5 and 6.

Spring 22 may assume the form of any closed convolution spring, while platform or support 10 may be made from any suitable metallic or plastic substance. Preferably, it is an integrally united light-weight plastic element formed by an appropriate injection molding or die casting process.

The foregoing description and the drawings are given merely to explain and illustrate my invention and the invention is not to be limited thereto, except insofar as the appended claims are so limited, since those skilled in the art who have my disclosure before them will be able to make modifications and variations therein without departing from the scope of the invention.

I claim:

1. A sash support adapted to be attached to coil spring sash balances by being inserted between the convolutions thereof, said support comprising a substantially planar web portion having a tapering lug projecting from one surface thereof and tapering increasingly in thickness inwardly of one edge of the web portion, and a pair of substantially coplanar oppositely extending flanges fixed to said web portion and disposed substantially parallel to the plane of said web portion, whereby, when said edge of said web portion is pressed between two adjoining spring convolutions to dispose said lug within the spring, said support is retained in the spring against lateral displacement.

2. A sash support adapted to be attached to a coil

spring sash balance by being inserted between adjacent convolutions thereof, said sash support comprising a platform member including a pair of oppositely projecting coplanar flanges, a relatively flat web portion intermediate said flanges and fixed thereto, said web portion being formed with a relatively thin edge along one side thereof adapted to be interposed between adjacent convolutions of the spring, and an arcuate wall projecting from the upper surface of said web portion, said wall terminating at end portions adjacent said edge on either side of said web portion to define with said web portion a spring convolution receiving pocket, said web portion carrying a wedge shape lug projecting from the lower surface thereof and increasing in thickness from a point adjacent to said edge of said web portion to a point inwardly thereof.

3. The support set forth in claim 2 wherein the under surfaces of said flanges are disposed below said lower surface of said web portion to define a second spring convolution receiving pocket at the underside of said member.

4. The support set forth in claim 2 wherein said arcuate wall is formed with symmetrically disposed right angle locating corners positioned respectively on the side of said web portion opposite said thin edge.

5. A sash support adapted to be attached to a coil spring sash balance by being inserted between adjacent convolutions thereof, said sash support comprising a body comprising a web portion and a pair of oppositely extending flanges affixed to said web portion, said flanges projecting from and extending in substantial parallelism with said web portion, said web portion defining an edge portion disposed between said flanges and proportioned to be interposed between adjacent convolutions of the spring, said body further including a wall structure projecting substantially normally of said web portion and defining with said web portion a spring convolution receiving pocket having an opening along said edge portion, said web portion carrying a tapered lug projecting from one of the surfaces thereof, said lug being spaced from said wall structure along the plane of said web portion and increasing in thickness inwardly of said edge portion of said web portion.

6. A sash balance unit comprising in combination a closed convolution coiled spring and a sash support secured to the spring by being received between adjacent convolutions thereof, said support comprising a body including a web portion and a pair of oppositely extending flanges affixed to said web portion and projecting outwardly of the spring on either side thereof, said web portion defining an edge portion disposed between said flanges thereof proportioned to be passed between said adjacent convolutions of the spring, said body further including a wall structure projecting substantially normally of said web portion and defining with said web portion a spring convolution receiving pocket having an opening along said edge portion, said web portion carrying a tapered lug projecting from one of the surfaces thereof, said lug being spaced from said wall structure along the plane of said web portion and increasing in thickness inwardly of said edge portion of said web portion.

55 7. A sash support adapted to be attached to a coil spring sash balance by being inserted between adjacent convolutions thereof, said sash support comprising a body including a web portion and a pair of substantially oppositely extending flanges projecting to either side of said web portion, said web portion defining substantially oppositely facing surfaces and an edge portion proportioned to be interposed between adjacent convolutions of the spring, said body including a wall structure projecting substantially normally of said web portion surfaces and defining with said web portion a spring convolution receiving pocket having an opening along said edge por-

65 70 75

tion, and a tapered lug structure carried by said web portion and projecting from one of said surfaces thereof, said lug structure being spaced from said wall structure along the plane of said web portion and increasing in thickness inwardly of said edge portion of said web portion.
